United States Patent Office.

W. M. KOHL, OF CINCINNATI, OHIO.

Letters Patent No. 76,472, dated April 7, 1868.

IMPROVEMENT IN STEREOSCOPES.

The Schedule referred to in these Letters Patent and making part of the same.

TO ALL WHOM IT MAY CONCERN:

Be it known that I, W. M. KOHL, of Cincinnati, in the county of Hamilton, and State of Ohio, have invented a new and improved Stereoscope; and I do hereby declare that the following is a full, clear, and exact description thereof, which will enable those skilled in the art to make and use the same, reference being had to the accompanying drawings, forming part of this specification.

This invention relates to a new and improved stereoscope or stereoscopic box; and it consists, first, in a new and improved application of the lenses to the box, whereby the former may be adjusted in two different directions, in order to obtain a proper focal distance, and to suit the width of the pictures. The invention consists, second, in an improvement pertaining to the scene or picture-holder, as hereinafter fully shown and described. In the accompanying sheet of drawings—

Figure 1 is a side sectional view of my invention.

Figure 2, a vertical section of the same, taken in the line *x x*, fig. 1.

Figure 3, a horizontal section of the same, taken in the line *y y*, fig. 2.

Figures 4 and 5, detached perspective views of the spring-clamps pertaining to the scene or picture-holder.

Similar letters of reference indicate corresponding parts.

A represents a quadrilateral box of any suitable dimensions, and provided with lids *B B* connected to the top of the box by hinges *u*, the under surfaces of said lids being covered with foil, or other suitable material, to serve as a reflecting surface. On the top of the box, underneath the lids, there is fitted a cover, *C*, of ground glass, which serves to distribute and mellow the light thrown upon the pictures. These parts are old and well known, and therefore do not require a specific description.

The picture-holder is constructed as follows: Horizontally through the lower part of the box *A* there passes a shaft, *D*, having a knob, *b*, on each end for the convenience of turning it, and to the inner surfaces of two opposite sides of the box there are secured vertical cleats *e*, between which there are fitted slides *d*. Between these slides there is placed a horizontal shaft, *E*, which is of rectangular form in its transverse section. Over this shaft *E* there is fitted an apron, *F*, constructed of any suitable flexible material, and having its ends connected by cords *e* to the shaft *D*, so that, by turning the shaft *D* first in one direction and then in the other, the apron *F* may be moved over shaft *E* in a corresponding manner, the movement of the shaft *D*, and consequently the apron, being limited in either direction by means of cords *f* attached to shaft *D* and the sides of the box, as shown in fig. 1. To the apron *F* there is attached in any suitable manner a series of bars, *g*, and to each bar *g*, near each end, there is attached a spring-clamp, *G*. These clamps are composed each of two springs *h h'*, secured to opposite sides of the bars, and curved, so as to press against the picture-cards *H*, which are inserted between them, the upper ends of the springs being curved or bent in semicircular form, so that they will, when pressed together, interlock and form a clasp, as shown in fig. 5, and thereby firmly retain or hold the picture-cards. By this arrangement the picture-cards may be fitted to and removed from the picture-holder with the greatest facility, and, when secured by them, firmly retained in position. To the ends or two opposite sides of the box *A*, there are attached hinged flaps *I I*, in which the tubes *J J* containing the lenses are fitted. These tubes are allowed to slide freely in sockets *K*, and the inner ends of the tubes have rectangular plates, or flanges *L* attached, the opposite edges of which are bent or curved to form tubes *i*, which are fitted loosely on rods *j*, so that they may slide freely thereon. The rods *j* of each flap *I* may be formed out of one piece, bent or curved, so as to have two parallel parts on which the flanges *L* slide, the bent or curved portion being so curved as to form an eye or nut, *k*, through which a screw, *M*, passes, said screw extending through the flap, and having a knob, *N*, on its outer end for the convenience of turning it. The ends of the rods *j j* pass loosely through a frame, *O O'*, hereinafter described. *O O'* represent two lever-frames, which are pivoted at one end to the flap *I*, the frame *O* having oblong slots *l* made in it for the pivots *m* to pass through, (see fig. 3,) which slots admit of a requisite degree of play of the frame *O*. The other frame, *O'*, has its pivots passing through it without oblong slots, no play of said frame being required.

By this arrangement it will be seen that the lens-tubes *J J* may, by turning the screw *M*, be adjusted further forward or backward, and a proper focal distance obtained. The sockets *K K* in each flap are provided with nuts *n*, which are fitted on a right-and-left screw-rod, *P*, having a knob, *o*, on one end, for the convenience

of turning it. By means of this screw-rod, connected with the sockets K, through the medium of the nuts n, it will be seen that the lenses may be adjusted nearer together or further apart, as may be desired, and said lenses consequently adjusted to suit the size or width of the pictures, so as to insure perfect binocular vision in relation with the pictures.

I claim as new, and desire to secure by Letters Patent—

1. The combination of the bent rod j, screw m, and pivoted levers O O', with the plate L and lense-tubes J, all constructed, arranged, and operating substantially as described for the purpose set forth.
2. In combination with the above, I claim the right and left-hand screw P, having head, o, and passing through lugs n attached to sockets K K, as described for the purpose specified.
3. The spring-clamps G attached to the bars g of the picture-holder, and constructed in the manner substantially as and for the purpose specified.

W. M. KOHL.
